ISAAC APPLIN SHEPPARD, OF PHILADELPHIA, PENNSYLVANIA.

Design No. 3,945, dated March 29, 1870.

DESIGN FOR STOVE-ORNAMENT.

The Schedule referred to in these Letters Patent and making part of the same.

I, ISAAC A. SHEPPARD, of Philadelphia, county of Philadelphia, State of Pennsylvania, have invented and produced a Design for a Stove-Ornament, of which the following is a specification.

General Description.

The figure in the accompanying drawing represents my design for a stove-ornament, the principal feature of and central object in which consists of the figure of a man ascending a rocky hill, and carrying a flag bearing the word "Excelsior," the figure and its adjuncts being cast in relief on and forming part of the plate of a stove.

This principal figure occupies a position within a scroll and foliated ornament, the design of which is

too clearly illustrated in the drawing to need description.

Claims.

1. The central figure illustrated and described when cast on and forming a part of a stove-plate.
2. The design, consisting of the said central figure and surrounding ornaments.

In testimony whereof I have signed my name to this specification in the presence of two subscribing witnesses.

ISAAC APPLIN SHEPPARD.

Witnesses:

Wm. A. STEEL,
LOUIS BOSWELL.
